UNITED STATES PATENT OFFICE.

GABRIEL L. HEUGEL, OF LOS ANGELES, CALIFORNIA, ASSIGNOR OF ONE-HALF TO JOSEPH SUNDERLAND, OF SAME PLACE.

DESIGN FOR A PUZZLE.

SPECIFICATION forming part of Design No. 26,784, dated March 23, 1897.

Application filed November 30, 1896. Serial No. 614,001. Term of patent 3½ years.

To all whom it may concern:

Be it known that I, GABRIEL LOUIS HEUGEL, a citizen of France, residing at Los Angeles, in the county of Los Angeles and State of California, have invented and produced a new and original Design for a Puzzle, of which the following is a specification, reference being had to the accompanying drawing, showing the same.

10 The figure is a view of a puzzle, showing my design.

My new design for a puzzle consists in a frame A, composed of a head-and-neck-shaped section a, with a long and comparatively nar-

row loop a' hinged to the neck thereof, a ring 15 b, and a retaining device b' to temporarily hold the ring on the frame.

The characteristic features of the design are the head-and-neck-shaped portion with the hinged loop, which is about as long as the 20 head, but comparatively narrow.

What I claim is—

The design for a puzzle substantially as shown and described.

G. L. HEUGEL.
